DESIGN FOR A HAT

Sam Lish, New York, N. Y.

Application July 12, 1944, Serial No. 114,374

Term of patent 3½ years

(Cl. D3—13)

To all whom it may concern:

Be it known that I, Sam Lish, a citizen of the United States of America, residing in the city of New York, county of New York, and State of New York, have invented a new, original, and ornamental Design for a Hat, of which the following is a specification, reference being had to the accompanying drawing, forming part thereof.

The figure on the drawing is a side perspective view of a hat showing my new design. The opposite side is substantially the same as the side shown.

I claim:

The ornamental design for a hat, as shown and described.

SAM LISH.
